UNITED STATES PATENT OFFICE.

EDWIN F. FIELD, OF LEWISTON, MAINE.

BOILER-FEEDING MECHANISM.

SPECIFICATION forming part of Letters Patent No. 772,410, dated October 18, 1904.

Application filed October 20, 1903. Serial No. 177,765. (No model.)

To all whom it may concern:

Be it known that I, EDWIN F. FIELD, a resident of Lewiston, in the county of Androscoggin and State of Maine, have invented certain new and useful Improvements in Boiler-Feeding Mechanism; and I do hereby declare the following to be a full, clear, and exact description of the invention, such as will enable others skilled in the art to which it appertains to make and use the same.

My invention relates to an improved boiler-feeding mechanism, more particularly adapted for use on motor-vehicles, the object of the invention being to provide mechanism for giving to the boiler a large immediate water-supply, feeding automatically cold water at the bottom of the boiler to replace water vaporized by the generation of steam therein, and prevent the necessity of the constant watching of the water-level in the boiler and consequent danger due to the fall of water thereon, and dispensing with the necessity for a frequent operation of the force-pump.

A further object is to provide an improved feed tank or tanks between the water-reservoir and boiler in direct communication at top and bottom with the boiler and into which tanks water from the reservoir is forced by a pump or other approved means; and a further object is to provide improvements of this character wherein the feed tanks or tank can be supplied with water without recourse to the reservoir and pump.

With these objects in view the invention consists in certain novel features of construction and combinations and arrangements of parts, as will be more fully hereinafter described, and pointed out in the claims.

In the accompanying drawings, Figure 1 is a perspective view illustrating my improvements. Fig. 2 is a view in vertical section on the line $\alpha\alpha$ of Fig. 1; and Fig. 3 is a view in elevation, partly in section.

1 represents a boiler which may be of any approved construction, but preferably of that type known as "tubular" to give to the boiler the maximum amount of heating-surface, and 2 represents an ordinary water reservoir or

tank, located, as shown, adjacent to the boiler or disposed some distance therefrom, as preferred.

3 indicate my improved feed-tanks, which are constructed, preferably, as shown, with inclosing pipes 4, surrounding tie-rods 5, which latter connect the tank-heads, to give to the tanks sufficient strength to withstand the boiler-pressure. The tanks 3 are both connected at their top with the top of boiler 1 by pipes 6 for conveying steam from the boiler to the tanks, and valves 7 are located in said pipes, which permit the steam-pressure to be shut off when desired. The bottom of said tanks 3 are connected with the bottom of boiler 1 by means of pipes 8, having a downward coil or bend 8^a therein, and are provided with valves 9 to shut off the passage of water, all for a purpose which will hereinafter appear.

A suitable pump 10 is provided for forcing water from reservoir 2 through pipes 11 into tanks 3, and funnel-shaped inlet-ports 12 are located on the top of tanks 3 and are normally closed by valves 13.

The operation of my improvements is as follows: The tanks 3 and boiler 1 are filled to the desired level either by means of pump 10 or through inlet-ports 12, and, as will be readily understood, the water will find a common level in the tanks and boiler. As the boiler is heated to generate steam therein the steam will pass through pipes 6 into tanks 3, maintaining a uniform pressure in the tanks and boiler, and owing to the well-known fact that hot water always rises and never descends the cold water from tanks 3 will feed through pipes 8 into the bottom of the boiler to replace the losses by evaporation and always maintain a uniform level in the boiler and tanks, and owing to the downward coil or twist 8^a in said pipes 8 there can be no return from the boiler to the feed-tanks due to the principle above mentioned. It will thus be seen that the boiler is provided with a large immediate supply automatically feeding to the boiler and insuring a long run of the engine without attention. If from any reason the pump

should not work, as is often the case, valves 7 and 9 can be closed, cutting off all communication with boiler 1 and valve 13 can be opened, water being then supplied by hand 5 through the funnel-shaped inlet-ports 12. Valve 13 can then be closed and valves 7 and 9 opened, when the boiler will be again ready for a long operation.

By providing my improvements the necessity for constantly watching the water-level 10 in a boiler is obviated, for the tanks 3 maintain an immediate supply which will last for a long period and relieve the operator of a great amount of worry he has been heretofore 15 subjected to and will also prevent the very frequent accidents due to a too great fall of water in the boiler.

A great many slight changes might be made 20 in the general form and arrangement of the parts described without departing from my invention, and hence I would have it understood that I do not restrict myself to the precise details set forth, but consider myself at 25 liberty to make such slight changes and alterations as fairly fall within the spirit and scope of my invention.

Having fully described my invention, what I claim as new, and desire to secure by Letters Patent, is—

30 1. The combination with a boiler, of a feed-tank, a pipe connecting the tank and boiler at their upper ends, a pipe connecting the boiler and tank at their lower ends, said last-mentioned pipe having a coil therein depending 35 below the remaining portion of the pipe, and means for supplying water to said tank.

2. The combination with a boiler, of a feed-tank, a pipe connecting the tank and boiler at their upper ends, another pipe connecting 40 them at their lower ends, valves in said pipes, a valved inlet-port communicating with the top of the tank, said port being open above the valve, a water-reservoir, and means for

forcing water from the reservoir into the tank.

3. The combination with a boiler, of a feed-tank, a valved pipe connecting the top of the boiler and tank, a valved pipe connecting the lower ends of the tank and boiler, and having a downward coil or bend therein projecting 50 down below the bottom of the boiler, and means for forcing water into said tank.

4. The combination with a boiler, of feed-tanks adjacent thereto and having a combined capacity greater than the capacity of the 55 boiler, pipes connecting the upper ends of both of said tanks directly with the boiler for the passage of steam from the boiler to the tanks, pipes connecting the lower ends of the tanks with the boiler to convey water from the 60 tank to the boiler, and maintain a uniform level in the tanks and boiler, a water-reservoir, and means for forcing water from the reservoir into the tanks.

5. The combination with a boiler and a water-supply reservoir, of a feed-water tank communicating at its respective ends with respective ends of the boiler, means for forcing water from the supply-reservoir to the tank, and an auxiliary water-supply port for the 70 tank, independent of the water-reservoir.

6. The combination with a water-reservoir and a boiler, of a series of feed-water tanks located in proximity to said reservoir and boiler, each of said tanks communicating at 75 its respective ends with the respective ends of the boiler, a common water-supply pipe between the tanks and the reservoir and auxiliary water-supply ports for the tanks.

In testimony whereof I have signed this 80 specification in the presence of two subscribing witnesses.

EDWIN F. FIELD.
